CHARLES E. MILLER, OF PITTSBURGH, PENNSYLVANIA.

INSULATOR-SUPPORT.

1,143,983.

Specification of Letters Patent.

Patented June 22, 1915.

Application filed May 4, 1914. Serial No. 836,092.

To all whom it may concern:

Be it known that I, CHARLES E. MILLER, a citizen of the United States, and a resident of Pittsburgh, in the county of Allegheny and State of Pennsylvania, have invented certain new and useful Improvements in Insulator-Supports, of which the following is a specification.

My invention relates to insulator supports and involves improved supporting structure at the support end for receiving the insulator.

My invention concerns particularly that class of insulator supports in which a thimble in the form of a coil or helix of wire is used for the threaded seat of an insulator, and my invention concerns improved structure at the end of the support for receiving and coöperating with the thimble, particularly where the support is of solid metal. In prior structures involving the mounting of a wire thimble on a support such as a solid metal pin, the arrangement is such that the insulator is subjected to considerable strain when applied to the thimble for the reason that no provision is made to allow any spiral yield or movement of the thimble during application of the insulator or removal thereof. The turns of the wire thimble can perhaps spread apart or flatten or otherwise distort and this would allow some yield; but it is the inability to yield spirally that has caused such strain on and breakage of insulators. Insulators may hold for a while after being screwed in place but the strains and stresses caused therein during application will cause the insulator to break from slight blows or external strains when wire is applied thereto or when subjected to expansion and contraction during weather changes. Outside of such severe strains caused in the insulator, another drawback has been the inability to readily unscrew the insulator, the absence of spiral yield being also responsible for this.

The general purpose of my invention is therefore to overcome all these defects in prior structures, the main object being to provide construction and arrangement which will permit substantial spiral yield and movement of the turns of the wire thimble both when the insulator is screwed thereto or unscrewed therefrom, such yielding limiting localized and concentrated strains on the insulator and preventing breakage there-

of while at the same time provision is made to allow the turns of the thimble to exert sufficient and uniform pressure against the insulator to lock it in its service position.

In prior supports of this class there has also been considerable breakage at the top of the insulator, the top being broken out upon engagement thereof with the top of the pin when the insulator is screwed down into place. There is either such breakage when the insulator is thus screwed down or the top is put to considerable strain which will result in breakage later on.

Another object of the invention is therefore to protect the insulator against such breakage by utilizing one or more turns of the wire thimble as a yielding abutment for the insulator top.

Generally speaking, the invention comprises a support such as a metal pin threaded with a long pitch a distance downwardly from its end and provided below the threaded section with a belt of longitudinally extending ratchet teeth, the wire thimble having its intermediate coils only arranged for receiving the insulator and having its upper and lower turns of smaller diameter and of a pitch to engage with the threads of the support, the upper end of the wire being shaped to form an abutment to limit the bodily downward movement of the thimble, and the lower end of the wire having a projection for engaging with the ratchet teeth to allow spiral movement of the lower turns on the threaded section when the insulator is screwed in place but to prevent spiral movement of such turns when the insulator is unscrewed.

The details of the construction and arrangement and the purposes and functions thereof will be clearly understood by reference to the accompanying drawings in which—

Figure 1 is an elevational view of the upper part of a supporting pin showing the thimble applied thereto ready to receive an insulator; Fig. 2 is a front elevational view of the entire supporting pin showing the position of the thimble after the insulator has been fully applied thereto, Fig. 3 is an elevational view of the upper part of the pin showing the thimble in vertical diametral section and in the position when an insulator has been applied thereto, Fig. 4 is a top view of Fig. 1, Fig. 5 is a sectional

100

105

110

view on plane 5—5, Fig. 3, and Fig. 6 is an elevational view of the support end showing a modified arrangement.

My invention is applicable to different structures of pins but the drawing shows it applied to a steel pin of the well known shape comprising a body part 10 above the seat 11, and a shank 12 which is threaded at its end for receiving the nut 13, the shank in practice being inserted through a suitable opening in the cross arm to be clamped between the seat 11 and the nut, the washer 14 being usually interposed. The upper end of the body part 10 is cylindrical and in accordance with my invention the upper end 15 thereof has a thread preferably rolled therein and this thread is of comparatively large pitch. Below the thread section I form a belt of longitudinally extending ratchet teeth 16 and notches 17 preferably rolled therein at the same time that the threading is formed. The insulator receiving thimble T is in the form of a coil of wire of suitable gage, the intermediate turns 18 being of diameters to receive insulators such as I, while the upper turns 19 and the lower turns 20 are of smaller diameter and of a pitch corresponding to that of the thread 15, the thread groove 15' being preferably of such an arc as to intimately receive the turns 19 and 20. The upper end *t* of the wire is deflected radially to form an abutment for limiting the downward bodily movement of the thimble, and the lower end 35 of the wire is provided with a radially inwardly extending ratchet projection or tooth *t'* for coöperating with the ratchet teeth 16 and notches 17. This tooth can readily be deflected from the wire by punching the 40 notch *n* at the outside of the wire in the manner well understood.

The purposes and results of the improved construction and arrangement are apparent. The thimble is formed up separately and 45 then screwed lightly on to the pin until the tooth *t'* reaches the ratchet section of the pin. The insulator is then applied and as the intermediate turns 18 of the thimble increase slightly in diameter downwardly in 50 accordance with the taper of the insulator interior, the insulator when screwed down will exert friction on the turns and if such frictional engagement is resisted by the turns the thimble will be rotated around the pin, the 55 tooth *t'* clicking over the ratchet teeth and engaging in successive notches 17. After the insulator and thimble have thus been turned a distance, the end *t* will abut firmly against the pin end and will lock the upper turns 19 60 against further downward bodily movement. Then as the insulator is further forced down and its smaller diameter threads engage with the larger diameter turns of the thimble this together with the 65 increasing friction will tend to contract the

turns and to cause spiral creeping thereof. On account of the freedom of the lower turns 20 to rotate, such contraction and creeping can readily take place and these lower turns continue in their rotation about 70 the pin to carry the tooth *t'* farther along the teeth, the turns 18 of the pin then moving bodily downwardly during their contraction and spiral creeping until the insulator is in place. This spiral creeping or 75 give and uniform yield of the turns will allow such application of the insulator with very little force compared to the force necessary in other structures of this class. The recoil of the turns upon release of the insulator after the screwing on operation will also be uniform against the insulator and will lock it firmly in place. The turns 18 also yield during construction work and during 80 service of the insulator, for example, the coils will yield while a wire is being tied to the insulator, and will yield to pull on the wire during service, such yield, however, being sufficient only to prevent breakage of 85 the insulator. 90

My improved arrangement has the decided advantage over prior structures in that it allows such ready and easy removal of the insulator. After the insulator has been screwed into position the lower turns, by the engagement of the tooth *t'* with one of the ratchet teeth 16, will be locked against unscrewing and will not turn when the insulator is turned for the purpose of unscrewing it. However, the upper turns 19 of the 95 insulator are free to unscrew and therefore as the insulator is unscrewed the turns 18 are free to contract and creep spirally, the creeping being taken up by the unscrewing of the upper turns 19. Owing to this 100 freedom of the turns 18 on account of the rotatable upper turns 19 the insulator can be removed with very little effort. After removal of the insulator the thimble can be readily removed by unscrewing the lower 105 turns 20 by the application of a suitable tool such as a screw-driver to shift the tooth *t'* across the ratchet teeth 16. After the thimble has been turned back to the position 110 shown in Fig. 1 it is ready for receiving the 115 same or another insulator.

In order to prevent straining or breaking of the top *i* of the insulator should the insulator be screwed down too far, I utilize 120 part of the thimble and the elasticity thereof to form a yielding cushion abutment for the insulator top. As shown Fig. 2, the upper end *t* of the wire is bent to be clear of the pin top when the base of this end reaches the pin top when the insulator is screwed in 125 place (see Fig. 3). Then when the insulator is screwed down as shown in Fig. 2, its top *i* will encounter the end *t* and the pressure of the top against this end will be taken up by part of the upper turns and owing to the 130

resiliency of these turns there will be yield to the pressure and breakage of the insulator top will be prevented. The end *t* is preferably bent sufficiently to withhold its sharp edge from the insulator and to present a curved surface thereto. Instead of having the end *t* of the wire deflected upwardly as shown in Figs. 1 to 4, it could be deflected downwardly to engage the pin with its point 10 and to offer the bend *b* as a seat for the insulator top.

I thus provide very efficient and desirable structure and arrangement in supports for insulators which will allow ready application of an insulator and particularly ready removal thereof. All concentrated and localized strains on the insulator are eliminated, the resistance and pressure being uniformly distributed, and the supporting 20 thimble turns being free to take care of all expansion and contraction of the insulator both radially, longitudinally and spirally. All this together with the cushion abutment provided for the insulator top will greatly 25 reduce breakage and will increase the life of the insulator. Although the insulator can be readily and easily screwed on or unscrewed it will be firmly held against self-displacement during service, and sudden 30 jars, blows, or pulls on the insulator during construction work or during service will be taken up by the yielding support and the insulator will be saved.

I do not, of course, desire to be limited to 35 the precise construction and arrangement shown and described as changes are no doubt possible which would still come within the scope of the invention.

I claim as follows:

40 1. An insulator support comprising a body having a threaded section, and a thimble in the form of a wire coil having some of its turns of a diameter and pitch to detachably fit the threaded section and having 45 other turns spaced away from the threaded section for receiving an insulator.

2. An insulator support comprising a body part having a threaded section, and a thimble in the form of a wire coil having 50 turns at its upper and lower ends of a diameter and pitch to detachably fit the threaded section, the intermediate turns being spaced away from the threaded section to receive an insulator.

55 3. An insulator support comprising a body part having a belt of ratchet teeth a distance below its upper end, and a thimble in the form of a wire spiral, the lower end of said wire being toothed to coöperate with 60 said ratchet teeth to prevent rotation of the thimble in one direction.

4. An insulator support comprising a body part having a belt of ratchet teeth a distance downwardly from its upper end, and a thimble in the form of a wire spiral,

the lower turns being contracted to closely fit the body part and being toothed to co-operate with the ratchet teeth to lock the thimble against rotation in one direction, the upper end of the spiral being contracted 70 to form an abutment to limit the downward movement of the thimble on the body part.

5. An insulator pin comprising a body part having its upper end threaded, an insulator receiving thimble adapted at its 75 lower end for detachable engagement with said threaded end whereby said thimble may be screwed on to the body part, means at the upper end of the thimble for limiting the downward travel of the thimble, and co-operating means at the lower end of the thimble and on the body part for locking the thimble against removal after application 80 thereof to the body part.

6. An insulator support comprising a 85 body part having its end section threaded, an insulator receiving thimble having an intermediate part adapted for coöperation with an insulator, a belt of ratchet notches below the threaded section on the body part, 90 the lower end of said thimble being contracted and threaded to detachably engage the threaded section and having a projection for coöperating with the ratchet notches to lock the thimble against removal after application 95 thereof to the body part.

7. An insulator support comprising a body part having its end section threaded, an insulator receiving thimble having an intermediate part adapted for coöperation 100 with an insulator, a belt of ratchet notches below the threaded section on the body part, the lower end of said thimble being contracted and threaded to detachably engage the threaded section and having a projection for coöperating with the ratchet notches to lock the thimble against removal after application thereof to the body part, the upper end of the thimble being contracted 105 sufficiently to abut against the top of the body part to limit the downward travel of the thimble.

8. An insulator support comprising a body part having its end section threaded, an insulator receiving thimble having an intermediate part adapted for coöperation 110 with an insulator, a belt of ratchet notches below the threaded section on the body part, the lower end of said thimble being contracted and threaded to detachably engage the threaded section and having a projection for coöperating with the ratchet notches to lock the thimble against removal after application 115 thereof to the body part, the upper part of the thimble being contracted 120 and threaded to also engage the threaded section.

9. An insulator support comprising a cylindrical stem having its upper section threaded and having a belt of ratchet 125

- notches below said threaded section, a thimble in the form of a wire helix, the intermediate section of said helix being of a diameter and pitch to receive an insulator 5 and the upper and lower ends being contracted and of a pitch to fit the threaded section, the lower end of the helix having a tooth for coöperating with the ratchet notches to allow screwing on of the thimble 10 but to prevent unscrewing thereof from the pin, the upper end of the helix wire being deflected radially to abut against the top of the pin to limit the downward travel of the helix thereon.
- 15 10. In an insulator support, the combination of a stem having its upper end section threaded and having a belt of ratchet teeth below said threaded section, a thimble in the form of a wire helix, the intermediate turns 20 of said helix being of a diameter and pitch to threadedly receive an insulator, the lower turns of the helix being contracted and of a pitch to fit the threaded section and having a detent projection for coöperating with the ratchet teeth to lock the helix against unscrewing from the stem, the upper end of 25 the helix being contracted to form an abutment for engaging the top of the stem when the lower turn reaches the ratchet belt whereby when an insulator is screwed on to 30 the intermediate section the helix will be prevented from bodily downward travel but will be allowed to contract and shift spirally on account of the ability of the lower turn to rotate, the engagement of the toothed lower turns with the ratchet teeth then locking the lower end of the helix to allow contraction and spiral movement of the intermediate turns when the insulator is unscrewed.
- 35 11. An insulator support comprising a pin having its upper end section threaded and having a belt of ratchet teeth below the threaded section, a thimble in the form of a 40 wire helix having its lower and upper turns of a diameter and pitch to threadedly engage the threaded section, the intermediate turns being of larger diameter and pitch to receive an insulator, a projection at the lower end of the helix for coöperating with 50 the ratchet teeth to allow screwing on of the thimble but to prevent unscrewing thereof, the upper end of the helix wire being contracted and bent to abut against the pin top to prevent bodily downward movement of the thimble after the lower end thereof comes into coöperation with the ratchet teeth.
- 55 12. An insulator support comprising a stem having its end section threaded, a thimble in the form of a helix having its lower end contracted and of a pitch to fit the threaded section and having the threaded section above such lower section of larger diameter and of a pitch to receive an insulator, and means adapted upon unscrewing movement of the insulator to prevent unscrewing movement of said lower section but to permit the upper section to move spirally in order to contract to allow 60 ready removal of the insulator.
- 65 13. An insulator support comprising a stem having a section below its upper end threaded, a thimble in the form of a wire helix having its lower end contracted and of a pitch to fit the threaded section and having the section above such lower end of the diameter and pitch to receive an insulator, means for limiting the downward movement of the helix on the pin, and means 70 for allowing screwing of the lower end along said threads but for automatically preventing unscrewing movement thereof.
- 75 In witness whereof, I hereunto subscribe my name this 27th day of April, A. D., 80 1914.
